CLAIM

I claim the ornamental design for a garment hanger, as shown.

DESCRIPTION

FIG. 1 is a front perspective view of a garment hanger showing my new design;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a top plan view thereof;

FIG. 7 is a bottom plan view thereof;

FIG. 8 is an enlarged sectional view taken in the direction of the arrows on line 8—8 of FIG. 2;

FIG. 9 is an enlarged sectional view taken in the direction of the arrows on line 9—9 of FIG. 2;

FIG. 10 is an enlarged sectional view taken in the direction of the arrows on line 10—10 of FIG. 2; and,

FIG. 11 is an enlarged sectional view taken in the direction of the arrows on line 11—11 of FIG. 2.
